UNITED STATES PATENT OFFICE.

WILLIAM J. GAGNON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

BEAD-CHAIN.

1,078,494.

Specification of Letters Patent.

Patented Nov. 11, 1913.

Application filed May 27, 1913. Serial No. 770,260.

To all whom it may concern:

Be it known that I, WILLIAM J. GAGNON, a citizen of the United States of America, residing in the city of Bridgeport, county of 5 Fairfield, and State of Connecticut, have invented certain new and useful Improvements in Bead-Chains, of which the following is a specification.

My invention relates to the construction 10 and manufacture of chains of that class which are known as bead chains, and in which hollow balls are united together by links of approximately dumb-bell shape, the heads of each dumb-bell being inclosed within 15 the hollows of adjacent balls.

The main object of my invention is to improve the construction of the chain and facilitate its manufacture.

The accomplishment of this object is 20 secured essentially by constructing the dumb-bell portion of the chain out of tubular material instead of solid wire, as has been the common practice heretofore.

In the accompanying drawing, Figure 1 25 is an enlarged cross-sectional view of a tube from which the dumb-bell sections may be formed; Fig. 2 is an enlarged longitudinal section of a piece of such tubing with the dumb-bells formed thereon; Fig. 3 is an enlarged sectional view of a part of a bead 30 chain being constructed according to my invention.

The ordinary method of making bead chains consisting of hollow balls joined by 35 dumb-bell links has been to shape a length of solid wire by swaging into the form of a series of connected dumb-bells and then to feed this inside a tube of suitable diameter through a swaging machine, which would 40 form the outer tube into the shape of connected balls, each ball inclosing a pair of adjacent dumb-bell heads on the inclosed formed wire, and then breaking apart the connected balls and also breaking apart the 45 connected dumb-bells.

The proper formation of the internal headed wire has always presented difficulties, requiring considerable manipulation in the swaging dies and requiring also much 50 care to avoid forming of fins.

I have discovered that the production of a bead chain can be greatly facilitated and substantially closed links, free from fins, can be obtained by forming the dumb-bell links from tubular material. For this purpose I form a tube of a diameter less than the desired diameter of the heads of the dumb-bells. This tube may be formed in any suitable way, as by drawing a ribbon of the desired metal through a drawing die to 55 form a tube with longitudinal seam, such as indicated in the cross-sectional view, Fig. 1. Then, by means of suitable swaging dies, or otherwise, I shape the tube into the form of connected dumb-bells D, as illustrated in 60 Fig. 2. In this operation, the tubular form of the material operated on facilitates the compressing action needed to form the practically closed shanks of the dumb-bells and the connections between adjacent dumb-bell 65 heads, with the result that I am able to form the material into the desired shape easily and with comparatively few swaging actions and to produce substantially closed dumb-bell forms smooth and free from fins on the 70 exterior. Then the thus-formed rod of dumb-bells, such as indicated in Fig. 2, with an exterior tube of a diameter equal to that of the desired balls, is fed through dies which shape the outer tube into the form 75 of connected balls B over the pairs of dumb-bell heads, as indicated at the left of Fig. 3, and thereafter the connected balls B are 80 broken apart, and the dumb-bell links D are also broken apart to form the chain, as indicated at the right of Fig. 3.

I am aware of British Patent 7409 of 1905, and I do not claim anything therein disclosed.

I claim as my invention:

A bead chain consisting of hollow balls 90 with connecting dumb-bell links of tubular material, with substantially closed shanks.

In testimony whereof I have signed my name to this specification, in the presence of 95 two subscribing witnesses.

WILLIAM J. GAGNON.
